RESPIRATOR CONTROL VALVE CASING

Birchard M. Brush, Westminster, Colo., assignor to J. J. Monaghan Company, Inc., Denver, Colo., a corporation of Colorado

Filed Apr. 13, 1959, Ser. No. 55,704

Term of patent 14 years

(Cl. D83—1)

Figure 1 is a top plan view of a respirator control valve casing showing my new design, the bottom being substantially plain;

Figure 2 is a front elevational view thereof, the back being substantially plain;

Figure 3 is a right side elevational view thereof, the left side being substantially plain;

Figure 4 is a fragmentary vertical section taken through the right eye along line 4—4 of Figure 2; and,

Figure 5 is a fragmentary vertical section taken through the nose and mouth along line 5—5 of Figure 2.

I claim:

The ornamental design for a respirator control valve casing, as shown and described.
